[57] CLAIM

The ornamental design for an electrical cord connection, as shown and described.

DESCRIPTION

FIG. 1 is a perspective view of an electrical cord connection

1 Claim, 4 Drawing Sheets

showing my new design, the broken lines showing the electrical cord sections are for illustrative purposes only, and form no part of the claimed design;

FIG. 2 is a left side view thereof, the broken lines showing the electrical cord sections are for illustrative purposes only, and form no part of the claimed design;

FIG. 3 is a right side view thereof, the broken lines showing the electrical cord sections and the electrical prong connectors are for illustrative purposes only, and form no part of the claimed design;

FIG. 4 is a rear view thereof, the broken lines showing the electrical cord are for illustrative purposes only, and form no part of the claimed design;

FIG. 5 is a front view thereof, the broken lines showing the electrical cord are for illustrative purposes only, and form no part of the claimed design; and

FIG. 6 is a top view of my design, the broken lines showing the electrical cord sections are for illustrative purposes only, and form no part of the claimed design;

FIG. 7 is a bottom view thereof, the broken lines showing the electrical cord sections are for illustrative purposes only, and form no part of the claimed design; and,

FIG. 8 is a perspective view thereof showing the two portions of the electrical connection being separated, the broken lines showing the electrical cord sections are for illustrative purposes only, and form no part of the claimed design.
